UNITED STATES PATENT OFFICE.

CHARLES A. SON, OF SAN FRANCISCO, CALIFORNIA.

DESIGN FOR A TOY.

48,233.

Specification for Design.

Patented Nov. 30, 1915.

Application filed February 23, 1915. Serial No. 10,143. Term of patent 7 years.

To all whom it may concern:

Be it known that I, CHARLES A. SON, a citizen of the United States, residing in the city and county of San Francisco and State of California, have invented a new, original, and ornamental Design for Toys, of which the following is a specification, reference being had to the accompanying drawings, forming part thereof.

The figure is a perspective view of a toy illustrating my new design.

I claim:

The ornamental design for a toy, as shown.

CHARLES A. SON.

Witnesses:

JULIUS JACOBS,
F. SPANGENBERG.
